METHOD OF REMOVING SPIRALLY WOUND ARTICLES

William P. Campbell, Baltimore, and Fred N. Dailey, Ruxton, Md., assignors to Western Electric Company, Incorporated, New York, N. Y., a corporation of New York

Application July 12, 1950, Serial No. 173,424

4 Claims. (Cl. 18—48)

1

This invention relates to methods of removing spirally wound articles from supports on which they are wound, and more particularly to methods of removing retractile telephone cords, and the like, from mandrels on which they are wound.

One type of retractile telephone cord is made from cordage having a plurality of individually insulated conductors enclosed in a vulcanized jacket. A length of such cordage is wound on a mandrel into a helix so that the adjacent turns abut each other, and then is subjected to sufficient heat to set the cordage in its helical form after which it is cooled. Usually, the application of heat to the cordage causes the cordage to adhere to the mandrel, and also causes the adjacent convolutions of the helical cordage to stick together. As a result, it is an arduous and time consuming task to remove the cordage manually from the mandrel. Heretofore, no satisfactory method has been developed to remove lengths of retractile cordage from mandrels on which they are wound.

An object of the invention is to provide new and improved methods of removing spirally wound articles from supports on which they are wound.

Another object of the invention is to provide new and improved methods of removing retractile telephone cords, and the like, from mandrels on which they are wound.

A method of removing a spirally wound article from a support on which it is wound illustrating certain features of the invention may include effecting relative longitudinal movement between such a support and a gripper in engagement with the article, and effecting relative rotation between the gripper and the article in such a direction that the gripper tends to unwind the article from the support.

Other objects and advantages of the invention will appear from the following detailed description of methods forming specific embodiments thereof, when read in conjunction with the appended drawing, in which:

Fig. 1 is a side elevation of a compact helix of retractile cordage wound on a mandrel;

Fig. 2 is a fragmentary, side elevation in partial section of an apparatus useful in performing methods embodying the invention.

Fig. 3 is an enlarged transverse section taken along line 3—3 of Fig. 2, and

Fig. 4 is an enlarged, fragmentary, longitudinal section of a portion of the apparatus shown in Fig. 2.

Referring now in detail to the drawing, Fig. 1

shows a length of multi-conductor cordage 10 wound under tension on a mandrel 11 into a compact helix 14, in which the adjacent convolutions of the helix abut each other. The opposite ends 5 of the helix 14 are secured in clamps 15 and 16 fastened rigidly to the mandrel to hold the helix in its tightly wound form on the mandrel. The cordage 10 may include a plurality of individually insulated conductors (not shown) enclosed in a vulcanized jacket. The jacket of the cordage 10 may be made principally of rubber or rubber-like compounds, or other types of vulcanizable elastomeric compounds which may be cured by the application of heat and pressure into a tough, 15 elastic material.

After the cordage 10 is wound on the mandrel 11 in the manner described, the compact helix 14 is positioned in an oven to heat the cordage sufficiently to release strains in the jacket of the cordage 10 and then is cooled to set the jacket in its helical form so that the cordage will remain in a resilient helix after it is removed from the mandrel. The jacket on the cordage 10 may be only partially vulcanized or it may be fully vulcanized 20 or cured into a tough, elastic state before it is wound on the mandrel 11. In either instance, the application of additional heat to the cordage 10 causes the jacket of the cordage to adhere to the mandrel 11 and causes the adjacent convolutions 25 of the helix 14 to stick together. As a result, when the clamp 16 is removed from the mandrel 11, the helix 14 does not unwind so that its internal diameter remains at the same diameter as that of the mandrel. Therefore, to remove the helix from the mandrel, the convolutions must be separated 30 from each other and from the mandrel 11 so the helix 14 can unwind and be removed readily from the mandrel.

A small electric gear-motor 20 positioned on a 40 suitable table 21 has an output shaft 22 to which a coupling 23 is keyed. The coupling 23 is designed to receive a chuck 24 composed of a vulcanized compound and having an internal bore designed to grip the end of an elongated tube 25. The tube 25 has an internal bore 27, which is 45 slightly larger than the outside diameter of the mandrel 11, so that the tube may be slid over the mandrel, and has a tapered free end portion 28, as seen in Fig. 4.

The gear-motor 20 is arranged to drive the member 25 in a clockwise direction, as viewed in Fig. 3, which is opposite to the direction in which the helix is wound on the mandrel. The chuck 24 is preferably made of hard rubber so that it 55 will break if the load on the chuck exceeds a

predetermined amount, but may be made of other materials that will accomplish the desired result. The tube 25 may be made of any suitable metal or plastic material such as Bakelite, and has a smooth outer surface.

Operation

To remove the helix 14 from the mandrel 11 after it has been heated and cooled to set the cordage in its helical form, the clamp 16 is removed from the end of the mandrel, and is disengaged from the cordage. The end of the mandrel from which the clamp 16 has been removed is inserted into the tube 25 and the mandrel is held against rotation. Let it be assumed that the motor is rotating the tube 25 in a clockwise direction, as viewed in Fig. 3, and that the cordage 10 is wound on the mandrel 11 in a counterclockwise direction. After the end of the mandrel 11 is inserted manually into the tube 25 (Fig. 2), the mandrel and the helix are moved to the right until the right end of the helix 14 presses against the tapered end 28 of the tube 25. As the tapered end of the rotating tube 25 engages the end convolutions of the helix, it exerts a frictional force thereon which tends to unwind the helix, and also tends to lift the cordage from the mandrel. This tendency of the tube to unwind the helix and pry it from the mandrel, pulls the convolution loose from the mandrel and at the same time pulls each convolution loose from the adjacent convolutions. As each portion of the helix is freed from the mandrel and from the rest of the helix, it slides up onto the outer surface of the tube 25, and the tapered end of the tube engages the next portion of the helix.

Continued movement of the helix 14 to the right causes the end of the tube 25 to exert a frictional force incrementally on all the convolutions of the helix sufficient to separate them from the mandrel and from each other, and they slide on the member 25. When the tube engages the clamp 15, the entire helix 14 is free from the mandrel 11 and the mandrel then is withdrawn from the tube 25 and the helix slides off the tube. The end of the cordage 10 is removed from the clamp 15, and the helix is removed from the mandrel. When the helix 14 has been freed from the mandrel, in the described manner, it unwinds slightly and assumes an outside diameter larger than that to which it was wound on the mandrel 11 and an internal diameter slightly larger than the diameter of the mandrel 11. As a result, the helix 14 may be slid easily off the mandrel 11 after the end thereof has been released from the clamp 15. If the tube 25 should suddenly grab the helix and tend to turn the helix and the mandrel, which would result in the tube breaking the helix, the chuck 24 is designed to break. This feature prevents the tube from damaging the helix or cordage when these conditions occur.

It is to be understood that the tube 25 may be used as a support for holding the helix in shape during packaging and shipping of the retractile cord. This result is obtained by releasing the end of the helix from the clamp 15 after the entire helix 14 is transferred to the tube and withdrawing the mandrel 11 from the tube. Then the tube supporting the helix is removed from the chuck 24 and another tube is inserted therein. The above-described arrangement eliminates removing the helix from the tube and subsequently placing a dowel in the

helix to hold it in shape until the cord is installed in service.

If desired the mandrel 11 and the helix 14 might be rotated in the direction in which the helix is wound on the mandrel, and the tube 25 be held against rotation. The rotation of the helix causes the tube to tend to unwind the convolutions of the helix and lift them from the mandrel so that they slide onto the tube as the helix is moved longitudinally along the tube. Also, the tube may be moved longitudinally with respect to the helix and accomplish the same result.

While the above-described methods are particularly well adapted to remove retractile cords from winding mandrels, they may be readily modified to remove various types of helically wound articles from winding supports without departing from the spirit and scope of the invention.

What is claimed is:

1. A method of removing a spirally wound article from a support on which it is wound, which comprises effecting relative longitudinal movement between a tube and the support so that the tube engages the inner surface of the convolutions of the article wound thereon, and simultaneously effecting relative rotation between the tube and a portion of the article in such a direction that the tube unwinds the article from the support and transfers the convolutions to the tube.

2. A method of removing a spirally wound article from a support on which its convolutions are wound and stuck, which comprises rotating a tubular member in a direction opposite to that in which the article is wound on the support, inserting the rotating member between the support and the convolutions at one end of the article, holding the article and its support against rotation while advancing the rotating member between the support and successive convolutions of the article to lift and slide them onto an outer surface of the rotating member, and sliding the article off the rotating member after all the convolutions are transferred from the support to the member.

3. A method of removing a helically wound article from a mandrel on which it is wound, when its convolutions are stuck together and to the mandrel, which comprises passing a tubular member between the inner surface of the convolutions and the outer surface of the mandrel and simultaneously rotating the tubular member in a direction opposite to the direction in which the article is wound on the mandrel, holding the article and mandrel against rotation whereby the rotating member unwinds the convolutions from the mandrel and separates them from the mandrel and from each other, whereby they slide onto the outer surface of the tubular member, and sliding the article off said member.

4. A method of removing a helically wound retractile cord from the mandrel on which it is wound when its convolutions are stuck together and to the mandrel, which comprises removably attaching a tube to a rotatable chuck, rotating the chuck and the tube in a direction opposite to that in which the cord is wound on the mandrel, inserting an end of the mandrel into the tube so that the end of the tube enters between the mandrel and the convolutions of the cord, holding the mandrel and cord against rotation, gradually advancing the mandrel through the

tube so that the tube unwinds and slides the convolutions of the cord onto the tube, withdrawing the mandrel from the tube so as to leave the cord helically wound on the tube, and removing the tube from the chuck, whereby the tube may be used to prevent damage to the retractile cord during packaging and shipping of the cord.
